Radio Corporation of America, a corporation
of Delaware

Application June 11, 1941, Serial No. 397,536

10 Claims. (Cl. 179—171)

My present invention relates to regenerative systems, and more particularly to a novel, and improved, method of stabilizing regenerative transmission networks.

As is well known, regenerative amplifier circuits may often give rise to slight instabilities due to various factors. In the first place variations in circuit constants, particularly where small trimmer condensers are used, may cause instability. Secondly, variation in the different tubes due to ordinary manufacturing differences, or aging effects, will cause instability. Thirdly, variations in the power supply voltage will give rise to unstable conditions. While it is possible to minimize instability due to variations in circuit constants, as for example by using permeability tuning in place of physical condensers, yet instability due to the other factors is not easily remedied.

Accordingly, it is one of the main objects of my present invention to provide a method of, and means for, stabilizing regenerative circuits wherein a special control electrode is employed in the regenerative tube to provide a reactive effect across the regenerative output circuit, and the reactive effect being such as slightly to mistune the output circuit when unstable conditions arise.

Another important object of the invention may be stated to reside in the provision of a regenerative network, particularly adapted to provide a highly amplified carrier voltage for use in a demodulator employing an exalted carrier voltage, utilizing a tube provided with a special control grid which has applied to it signal voltage which is in quadrature with the signal voltage applied to the normal signal control grid whereby a capacity effect is simulated across the regenerative output circuit, and the said capacity effect being of sufficient magnitude slightly to detune the output circuit in response to variations in the transconductance of the regenerative tube sufficient to cause instability.

Still other objects of the invention are to improve degenerative amplifier circuits, and more especially to provide a stabilized regenerative circuit which is not only reliable and efficient in operation but which is economically manufactured and assembled.

The novel features which I believe to be characteristic of my invention are set forth in particularity in the appended claims; the invention itself, however, as to both its organization and method of operation will best be understood by reference to the following description taken in connection with the drawing in which I have in-

dicated diagrammatically a circuit organization whereby my invention may be carried into effect.

In the drawing:

Fig. 1 shows a circuit diagram of a regenerative circuit embodying the invention,

Fig. 2 graphically illustrates the functioning of the invention.

While the present invention is explained in connection with the second detector circuit of a receiver of the type shown in my application Serial No. 335,892, filed May 18, 1940, now Patent No. 2,243,141 dated May 27, 1941, yet it will be understood that the stabilized regenerative amplifier may be employed in any other circuit suitable for utilizing regeneration. Briefly, in the aforesaid application it has been shown that a highly improved rejection of interference can be secured if there is injected into the demodulator circuit highly amplified oscillations derived from the signal energy and having substantially all modulation side bands removed. The phenomenon has been termed "phase detection," and the circuit involved is generally as shown in Fig. 1. The superheterodyne converter tube plate includes the resonant output circuit 3—4, and the latter is tuned to the operating intermediate frequency (I. F.) value of, for example, 425 kilocycles (kc.). The usual networks of a superheterodyne receiver precede the circuit 3—4.

30 The demodulator, or second detector, comprises the double diode tube 6 having a resonant input circuit. The latter consists of coil 7 coupled to primary coil 4. The condensers 8 and 9 are of equal value, and are in series across coil 7. The input circuit is tuned to the operating I. F. value. The anodes of the diode are connected to opposite sides of input circuit 7—8—9. The diode cathode is connected to the mid-point of coil 7 through load resistor 10 which is properly by-passed for I. F. currents by a condenser. The cathode end of the load resistor may be grounded; and audio voltage across the load is utilized in any well known manner.

45 The I. F. voltage for providing the "exalted," or highly amplified, carrier voltage is taken off through condenser 5 from the primary circuit 3—4. The sharply tuned regenerative network, including tube T, coil 40 and coil 51, substantially removes all the modulation side bands from the carrier; actually there might be components up to 400 cycles remaining on the I. F. carrier. The exalted carrier energy is applied to the junction of condensers 8 and 9 through a sharply tuned circuit 13—14 connected between said junction and ground. As explained in my aforesaid appli-

cation it is highly desirable to use a full wave rectifier as the demodulator, and to apply the exalted carrier in the balanced state shown. It is not believed necessary for the purposes of this application to explain the demodulation action any further, reference is made to my aforesaid application and Fig. 4 thereof for a specific explanation.

There are various factors which may give rise to a certain degree of instability in the regenerative circuit. These may be variation in circuit constants; variation in the characteristics of different tubes due to ordinary manufacturing differences or aging effects; variation in power supply voltage. One useful and advantageous step that can be taken to improve stability is to employ permeability tuning in the tuned circuits, and thus eliminate adjustable condensers. Hence, it is to be understood that the well known adjustable powdered iron core inductances may be utilized for tuning.

The regenerative tube per se is a pentagrid tube T, say of the 6A8 type, which has a cathode 28, a plate 21 and five intermediate grids 22, 23, 24, 25 and 26. The I. F. energy is fed to grid 22. The grid 22 is connected to ground by leak 30; cathode 28 is connected to ground by the usual self-biasing resistor R shunted by an I. F. by-pass condenser. Grids 23 and 25 are connected to a point of positive potential, and are, therefore, positive screen grids. The plate 21 is connected to a source of positive voltage through coil 40 shunted by a tuning condenser 41. The plate circuit is resonated to the operating I. F. value, and is reactively coupled to circuit 13-14 to provide sharp tuning.

Grid 24 is connected to the cathode through series coils 50 and 51. Coil 50 is coupled to the upper part of coil 40, the arrow therethrough indicating adjustable coupling. Coil 51 is reactively coupled to the lower part of coil 40, the coupling also being adjustable. The purpose of the coupling 50-40 is to neutralize the effect of inherent feedback between coils 4 and 7. The coupling 50-40 is degenerative, and exactly neutralizes regenerative coupling between coils 4 and 7 due to the regenerative tube.

Whereas in my previous application regenerative feedback was provided by a capacity coupling between the plate and grid of the regenerative tube, in this case coil 51 is inductively coupled to coil 40 to provide the required regenerative feedback. The coil 51 is connected in the opposite direction to coil 50. Grid 24 has, therefore, a dual function: to eliminate an undesired coupling, and to provide a controllable and desired coupling between the output circuit 40-41 and the input circuit 3-4. Normally these circuits are tuned to the I. F. value.

The voltage induced in coil 51 will be in exactly opposite phase to the voltage across coil 40 at resonance. Assuming the use of permeability tuning to eliminate variation in circuit constants, all other causes of variation will show up in a variation of the transconductance of tube T. An increase in this quantity will cause oscillation; a decrease will cause tube T to become less regenerative. Stabilization, therefore, requires a variable effect which is dependent upon transconductance, and acts in the reverse sense to the regenerative effect.

This reversely-acting effect is provided by grid 26 connected to the upper end of coil 2. The lower end of the coil is connected to the cathode, and the coil is loosely coupled to input coil 4.

Condenser 1 tunes coil 2 to the operating I. F. value. Here, again, coil 2 may be a permeability tuner. The voltage on grid 26 will be in quadrature with the voltage applied to input grid 22; the quadrature voltage may lead or lag. Assuming that it is a lagging voltage, then there will be a component of the plate current in quadrature with that due to grid 22 and it will be leading. It is, therefore, equivalent to a capacity in shunt with condenser 41, and the tuning of circuit 40-41 will in part be determined by the magnitude of the simulated capacity. This magnitude, in turn, will be determined by the coupling between coils 4 and 2 which is constant, and by the transconductance of tube T which is variable. Hence, it will be seen that there has been provided a means for automatically adjusting the resonant frequency of the plate circuit 40-41 in response to variations in transconductance of tube T.

Fig. 2 is a curve which represents variations in transconductance (g) plotted against variations causing changes in g . The curve is drawn in linear form, but might be of any other form. Let it be assumed that point A of the curve represents the average value of g for a given type of tube, while B represents the maximum value that it can conceivably assume under any operating conditions that may be met in practice. Point C on this curve represents a very small value of transconductance that can occur. In this latter case, tubes which are definitely inoperative or worn out are excluded, but tubes which have less than normal value of g when new, or are reduced in effectiveness by long service, are included. Point D represents a value of transconductance which is somewhat less than that of C.

Resistance R is assumed to be variable over a small range and with a tube T in place, it is so adjusted that the value of g corresponds to point D on the curve of Fig. 2. The input circuit 3-4 and the output circuit 40-41 are adjusted to exact tuning with the intermediate frequency, with the circuit 1-2 disconnected from the grid 26. Circuit 1-2 is then connected to its grid with some small value of coupling between coils 2 and 4. Circuit 40-41 will, then, have to be retuned while the circuit 50-51, previously assumed to be open, is adjusted in the manner already indicated. Assuming that the tube is adjusted to the point just below oscillation, with the transconductance corresponding to the point D, any increase in this quantity in the direction of C, A, B will cause an increase in the feedback, and, therefore, would result in oscillation production unless compensated for. At the same time, however, the quadrature current due to circuit 1-2 increases, which means that the capacity in circuit 40-41 increases, and it is, therefore, detuned. This detuning action will immediately reduce the feedback, and produce a compensating action. The magnitude of the detuning can be properly adjusted by adjusting the coupling between coils 4 and 2.

It is now apparent that as the transconductance increases, the detuning effect increases. Under normal operating conditions, the transconductance would have a value indicated at A, and the plate circuit would be somewhat detuned. If the line voltage dropped or the tube began to age, or both of these effects occur, the value of g will move toward points C and D, and the plate circuit would then be more nearly in tune with the operating I. F. value. On the other hand, if the line voltage became abnormally high, or if a tube

were substituted for T with an abnormally high value of g , then operating conditions would move toward the direction of B and the plate circuit would be detuned to a greater extent.

It is to be noted that the smaller the value of the condenser 41, the greater will be the effect due to circuit 1-2. The suppressor grid 28 which is used to produce the quadrature current has a controlling action which is small relative to the grid 22. A more powerful quadrature action is obtainable by interchanging grids 24 and 28. The amount of detuning necessary to produce the control action described above will be extremely small. In addition to the rapid falling off in intensity which will take place, there will be a shift in the phase angle of the voltage applied to the regenerative grid which will produce an additional reduction of the feedback. By making resistor R adjustable, it is possible to control the grid bias of grid 22, and, hence, the transconductance of tube T. When the circuits are adjusted at the proper point for regeneration, a very slight mistuning of circuit 40-41 will prevent it from oscillating, even with a large increase of the transconductance of the tube. It is, therefore, seen that only a very slight detuning action will be necessary to produce the required control action.

It is to be clearly understood, of course, that the present invention is in no way limited to the particular use shown. In other words, the stabilized regenerative circuit shown herein may be used in any situation where regenerative circuits are employed. Essentially what has been disclosed herein is a regenerative circuit which comprises a tube having at least one control electrode functioning to provide regenerative action, and a second control electrode cooperating with the input circuit to provide a reaction effect in the regenerative output circuit sufficient slightly to detune the output circuit thereby to prevent oscillation production should the transconductance of the regenerative tube increase for any reason beyond a desired normal operating condition representative of stabilized regeneration. If desired, the circuit 1-2 may be omitted, and the grid 28 may then be connected directly to 13-14 for the voltage thereof.

While I have indicated and described a system for carrying my invention into effect, it will be apparent to one skilled in the art that my invention is by no means limited to the particular organization shown and described, but that many modifications may be made without departing from the scope of my invention, as set forth in the appended claims.

What I claim is:

1. In combination with a tube provided with at least a cathode, a wave input electrode, a control electrode, an output electrode, a wave input circuit connected between said input electrode and said cathode, a wave output circuit connected to said output electrode, means regeneratively coupling said control electrode to said output circuit, means, reactively coupled to said input circuit, for controlling electrons flowing to said output electrode and providing a reactive effect across said output circuit whose magnitude is varied with the transconductance of said tube.

2. In combination with a tube provided with at least a cathode, a wave input electrode, a control electrode, an output electrode, a wave input circuit connected between said input electrode and said cathode, a wave output circuit connected to said output electrode, means regeneratively cou-

pling said control electrode to said output circuit, means, reactively coupled to said input circuit, for controlling electrons flowing to said output electrode and providing a reactive effect across said output circuit whose magnitude is varied with the transconductance of said tube, said last means including an auxiliary control electrode disposed in the electron stream flowing to said output electrode.

3. In combination with a tube provided with at least a cathode, a wave input electrode, a control electrode, an output electrode, a wave input circuit connected between said input electrode and said cathode, a wave output circuit connected to said output electrode, means regeneratively coupling said control electrode to said output circuit, means, reactively coupled to said input circuit, for controlling electrons flowing to said output electrode and providing a reactive effect across said output circuit whose magnitude is varied with the transconductance of said tube, said last means consisting of an auxiliary control electrode disposed between said control electrode and output electrode, and a resonant circuit, tuned to the frequency of applied waves, reactively coupling said input circuit to said auxiliary electrode.

4. In a regenerative signal transmission circuit, a tube provided with at least a cathode, an output electrode and at least three control grids arranged in successive order in the electron stream between the cathode and output electrode, a signal input circuit connected between the first grid and cathode, a signal output circuit connected between the output electrode and cathode, means regeneratively coupling the second grid to said output circuit to provide a desired regenerative feedback action, a third signal circuit connected to the third grid, said third signal circuit being reactively coupled to said signal input circuit in such a manner that a reactive effect is produced across said output circuit which is sufficient slightly to detune the output circuit in response to an increase in the transconductance of said tube above a predetermined transconductance value.

5. In combination with a tube provided with at least a cathode, a wave input electrode, a control electrode, an output electrode, a wave input circuit connected between said input electrode and said cathode, a wave output circuit connected to said output electrode, means regeneratively coupling said control electrode to said output circuit, an auxiliary grid in said tube, reactively coupled to said input circuit, for controlling electrons flowing to said output electrode and providing a reactive effect across said output circuit whose magnitude is varied with the transconductance of said tube.

6. In a regenerative signal transmission circuit, an electron discharge tube provided with at least a cathode, a plate and at least three control grids arranged in successive order in the electron stream between the cathode and plate, a signal input circuit connected between the first grid and cathode, a signal output circuit tuned to the input signal connected between the plate and cathode, means regeneratively coupling the second grid to said output circuit to provide a desired regenerative feedback action, a third signal circuit tuned to said input signal connected to the third grid, said third signal circuit being reactively coupled to said signal input circuit.

7. In a high frequency regenerative amplifier system, a tube provided with input and output

electrodes, a high frequency input circuit coupled to the input electrodes, a high frequency output circuit coupled to the output electrodes, a special regeneration grid in said tube, means providing regenerative feedback between the output circuit and the special grid, and means including an auxiliary electrode in said tube, responsive to variations in transconductance of said tube from a predetermined normal operating value, for regulating the current flow in said output circuit in a sense to stabilize the feedback.

3. In a regenerative signal amplifier system provided with signal input and output circuits, a tube having input and output electrodes coupled to said input and output circuits respectively, a control electrode in said tube for regeneration; means providing regeneration between the output circuit and said control electrode, an auxiliary electrode located within said tube, and means reactively coupling said auxiliary electrode to said input circuit in such a manner that signal voltage applied to the auxiliary electrode is in quadrature with the signal voltage applied to the input electrodes.

9. In a regenerative signal amplifier, a tube provided with at least a cathode, an output electrode and at least three control grids arranged

in successive order in the electron stream between the cathode and output electrode, a signal input circuit connected between the first grid and cathode, a signal output circuit connected between the output electrode and cathode, means regeneratively coupling the second grid to said output circuit to provide a desired regenerative feedback action, a third signal circuit connected to the third grid, said third signal circuit being reactively coupled to said signal input circuit in such a manner that signal voltage is applied to the third grid in quadrature relation relative to the signal voltage at the first grid.

10. In a high frequency amplifier, a tube provided with input and output electrodes and a special regeneration control electrode, a high frequency input circuit coupled to the input electrodes, a high frequency output circuit coupled to the output electrodes, means providing regenerative feedback between the output circuit and the special electrode, and means operative to control the electron flow in said tube, and responsive to variations in transconductance of said tube from a predetermined normal operating value, for regulating the current flow in said output circuit in a sense to stabilize the feedback.

ROY A. WEAGANT.
